Primary Examiner—Celia Murphy*(74) Attorney, Agent, or Firm*—Blackwell Sanders Peper Martin LLP(57) **CLAIM**

The ornamental design for a shoe sole, as shown and described.

DESCRIPTION

FIG. 1 is a bottom perspective view of a shoe sole showing our new design;

FIG. 2 is a bottom plan view thereof;

FIG. 3 is a front elevational view thereof;

FIG. 4 is a rear elevational view thereof; and,

FIG. 5 is a left side elevational view thereof, the opposite side being a mirror image.

The broken line showing a shoe upper in FIG. 1 illustrates a portion of a possible environment for the shoe sole, but forms no part of the claimed design. The surfaces which are not shown, form no part of the claimed design. The new design is for a shoe sole to be used on toy stuffed animals, such as teddy bears.
